Christopher J. Grellner
INVENTOR,
by Louis Gagger & Co
Attorneys,

UNITED STATES PATENT OFFICE.

CHRISTOPHER J. GRELLNER, OF ST. LOUIS, MISSOURI.

HAMMER.

SPECIFICATION forming part of Letters Patent No. 253,279, dated February 7, 1882.

Application filed June 28, 1881. (No model.)

To all whom it may concern:

Be it known that I, CHRISTOPHER J. GRELLNER, of St. Louis, in the county of St. Louis and State of Missouri, have invented certain new and useful Improvements in Hammers; and I do hereby declare that the following is a full, clear, and exact description of the invention, which will enable others skilled in the art to which it appertains to make and use the same, reference being had to the accompanying drawings, which form a part of this specification, and in which—

Figure 1 is a vertical cross-section of a hammer head and handle embodying my improvement. Fig. 2 is a top view of the hammer-head. Fig. 3 is a detail view of the peculiarly-constructed wedge for fastening the hammer-head upon its handle; and Fig. 4 is a similar view of a wedge of a slightly-modified construction, which is designated for use where my improvement is applied to wooden mallet-heads.

Similar letters of reference indicate corresponding parts in all the figures.

The object of my improvement is to provide a simple and efficient means of attachment of a hammer or mallet head upon its handle; and to this end it consists in the combination, with the head and handle, of a peculiarly-constructed wedge or fastening device, substantially as hereinafter more fully set forth, and particularly pointed out in the claims.

In the annexed drawings, A represents the hammer-head, which may be of any desired size and construction, and has a cylindrical aperture, B, for the insertion of the handle C. The eye or aperture B has two grooves, b b, opposite to one another, and the handle C has an annular groove, c, which, when the handle is inserted into its eye, will be in a line with the rounded lower ends, a, of the grooves b b in the hammer-head, which said grooves or recesses extend only about two-thirds down into the head, as will be seen by reference to Fig. 1.

The fastening devices or wedges D are of iron, of the shape shown in Fig. 3, with a lower bent or hooked end, d, having a notch, e, each wedge being somewhat longer than the depth of the

groove or recess b, into which it is inserted. 50 On the right side of the hammer-handle in Fig. 1 of the drawings I have shown the wedge D as it appears when inserted into its appropriate groove b and before it is rammed down, while on the opposite or left-hand side I have shown the wedge after it has been rammed down with its top flush with the hammer-head. 55 In this process of ramming down the wedge or fastener D its notched and hooked end d will, by the rounded bottom a of the groove b, be 60 driven into the wood of the handle at the annulus c, the notch e operating to facilitate the bending of the hooked end, which will fasten it and the hammer-head firmly upon the handle, so that it cannot by any possibility fly off. 65

If desired, the annular groove or channel c in the handle may be dispensed with, as the hooked and pointed ends of the wedges will work into the wood without it.

Where the wedges D d are to be used with a wooden mallet-head I prefer to construct them with a projecting spur, f, as shown in Fig. 4, which, in driving the wedge home in its recess, will work into the wood of the head at the same time that the point d works into 75 the wood of the handle.

Having thus described my invention, I claim and desire to secure by Letters Patent of the United States—

1. The hammer or mallet head A, having 80 the cylindrical handle bore or eye B and grooves or recesses b b, extending from the top of the head down into the same and terminating in rounded shoulders a a, substantially as and for the purpose herein shown and set forth. 85

2. The combination of the hammer-head A, having eye B and grooves or channels b b, rounded at their terminal points a a, wedges D D, terminating each in a notched hook, d, and the handle C, substantially as shown and 90 described, for the purpose set forth.

In testimony that I claim the foregoing as my own I have hereunto affixed my signature in presence of two witnesses.

CHRISTOPHER JOS. GRELLNER.

Witnesses:

JOS. W. PETERSEN,
E. H. KALKMAN.
